UNITED STATES PATENT OFFICE.

FORREST R. MAGUIRE, OF PITTSBURGH, PENNSYLVANIA, ASSIGNOR TO W. C. DAVIS, OF LARIMER, S. A. ACKERSON, OF TRAFFORD, AND W. L. KINSEY, OF PITTSBURGH, PENNSYLVANIA.

SELF-FEEDING APPARATUS.

1,333,209.

Specification of Letters Patent. Patented Mar. 9, 1920.

Application filed July 28, 1919. Serial No. 313,769.

To all whom it may concern:

Be it known that I, FORREST R. MAGUIRE, a citizen of the United States, residing at Pittsburgh, in the county of Allegheny and 5 State of Pennsylvania, have invented certain new and useful Improvements in Self-Feeding Apparatus, of which the following is a specification.

My invention consists of an improvement 10 in apparatus for feeding one's self by means of a spoon or fork or other similar device or utensil adapted to remove portions of food from a holding dish or plate, by means of actuating mechanism operated by the foot 15 or leg of the user. It has in view to provide such a device capable of use by a person having lost both his arms, or their use, and to enable him to transfer food from a vessel, which is itself preferably adjustable, 20 to a position where it may be easily taken into the mouth.

The present invention is an improvement on the particular type of machine disclosed in the prior application of Forrest R. Maguire, Serial No. 300,190, filed May 27, 1919.

Preferred embodiments of the invention are shown in the accompanying drawings, in which:

Figure 1 is a view of the apparatus in front elevation;

Fig. 2 is a side elevation partly broken away;

Fig. 3 is a plan view of the apparatus;

Fig. 4 is an enlarged view in side elevation, partly broken away, showing the feeding mechanism as used with a spoon in Fig. 2, in the operation of rising;

Fig. 5 is a similar view showing the spoon descending into the holding vessel;

Fig. 6 is a view similar to Fig. 4 showing the device and its controlling cam as utilized with a vertically descending fork;

Fig. 7 is a similar view showing the fork toward the termination of the rising movement, in position to deliver to the user;

Fig. 8 is a view similar to Fig. 6 but showing the device provided with a spoon attachment and arranged for vertical movement only in connection with a tilted vessel;

Fig. 9 is a vertical sectional view at right angles to Fig. 8 showing the spoon partly raised; and

Fig. 10 is a detail view showing rolling bearings for the vessel supporting plate.

55 The main base 2 of the apparatus is adap-

ted to be clamped to a table or shelf A by clamps 3 of any suitable construction, but preferably utilizing one or more vertically arranged stems 4 pivoted at 5 to a bracket depending from the main base, and having 60 a vertically adjustable arm 6 held at suitable position on stem 4 and provided with a securing set screw 6 at its terminal, whereby the base 2 may be clamped to the table A of any variable thickness. By means of 65 such clamps we are enabled to adapt the mounting of the device without adhering to any particular dimensions or size of the supporting table.

Slidably mounted upon the upper surface 70 of base 2 is a dish or vessel supporting plate 7, the front and rear edges of which ride along the inner faces of guiding strips 8, 8, extending upwardly from the base, or preferably from a covering plate thereof, for 75 easy movement. Supporting plate 7 is provided at its corners with upwardly extending posts 9 between which extend connecting supporting rods 10, upon which rest the rear portions of a series of dishes or holding vessels B, C, D. Said vessels, which may be 80 of any suitable shape or construction, are shown as rectangular and capable of being set either level or tilted at a slight inclination, as in Figs. 2, 4 and 5, for which mounting the rear cross rod 10 may be shaped accordingly. When tilted, the vessel may be used to contain fluid, as soup or any other similar material, and when flat may be used with food of a more solid character. With 90 either construction, the shape of the vessels adapt them to the forward sweeping action of a spoon in the manner illustrated in Figs. 1-5 inclusive, and as more fully hereinafter described.

95 For the purpose of manipulating plate 7 and its supporting vessels to the right or to the left of the user so as to bring each particular vessel or any portion of it within range of the feeding utensil, plate 7 is provided with a projecting stud 11 extending from one of the corner posts or otherwise suitably attached, having slotted engagement with the end of a lever 12. Said lever 12 is pivoted at 13 to a bracket 14 depending 100 from base 2 and is operated to the right or left by connecting rod 15 pivoted at 16 to a knee operated lever 17. Said lever 17 is pivoted at 18 to base 2 and is provided at its lower end with a double arm terminal 19 110

adapted to embrace the knee of the operator and to be moved to the right or left to effect lateral shifting to the vessel supporting plate. By this means, each particular vessel or any portion of it may be readily brought into range of the food holding utensil, as will be readily understood.

At one side of the normal middle position of the device, an upright plate 22 extends upwardly from base 2 to which it is rigidly secured, which plate constitutes the mounting for a guiding means for the principal actuating element thereof. Said element, in the form shown, is a vertically movable bar or strip 23 mounted in one or more guiding bearings 24 and extends downwardly sufficiently far below the base 2 to provide for ample range of movement and connection with the actuating cord or wire 25. Said cord is secured to the lower end of bar 23 as at 26, and cord 25 passes upwardly and around a guiding sheave 27 and is connected with the upper end of the shifting lever 28. Said lever is pivoted at its lower end at 29 in an upwardly extending bracket 30 of a pedal support 31 and is provided with an extended treadle 32 for engagement by the foot of the operator, as indicated in Fig. 2. A spring 33 is preferably provided whereby to assist in return movement of levers 28, in lowering the bar 23 by gravity.

At its upper end, bar 23 is turned backwardly providing terminal 34, to the end of which is pivoted at 35 the utensil holder 36. Said holder is preferably bent as at 37 to project the attaching terminal 38 somewhat outwardly beyond the operating mechanism to leave it free from interference therewith, and is adapted to be connected with the terminal spoon 39 by such connection, as will be readily understood. The specific construction of the connection is not essential and may be of the bayonet joint or other suitable type, whereby to insure easy attachment or removal of the utensil.

In its ordinary movement the terminal utensil may be raised and lowered vertically without lateral shifting, or may be controlled as to its movement so as to swing backwardly or forwardly, depending upon the utensil used and the kind of vessel. Thus, in the case of a spoon when used for lifting fluid, it is desirable that the spoon shall have a rear thrusting action on downward movement, a forward filling movement, and a vertical upward movement to deliver the contents in position to be taken into the mouth by the user. For such purpose, arm 36 is provided with a controlling pin 20 extending backwardly into range of an adjustable cam plate 21. Said cam plate is adapted to be thrust outwardly to inoperative position, as in Figs. 6, 7 and 8, or to be receded to operative position, as in

Figs. 4 and 5. For such purpose the cam plate 21 is pivotally connected at 40, 40 with the terminals of links 41—42 respectively pivoted at 43—43 to plate 22, whereby cam plate 21 is mounted somewhat outwardly beyond the face thereof.

For the purpose of adjusting cam plate 21 to operative or inoperative position, I provide an adjustable holding abutment 44 of generally triangular shape which is secured by its terminal at 45 to the end of an adjusting thumb terminal pin 46 at the other side of the plate. By this construction, abutment 44 may be thrust around under link 41 so as to maintain cam plate 21 outwardly in vertical inoperative position, as in Figs. 6 and 7, or may be thrust back as in Figs. 4 and 5, so as to allow the upper pivotal connection of the cam plate to recede and make it effective in manipulating the spoon for vertical upward movement and outwardly swinging down movement, by engagement with stud 20, as indicated in Fig. 5. Thus, when cam plate 21 is receded as shown in said figure, pin 20 will ride upwardly against the rear edge of the cam plate 21. Cam plate 21 will swing loosely with link 41 during upward movement of pin 20, but will fall backwardly to the position indicated in Fig. 5 after pin 20 has traveled above the upper terminal of the cam plate. Thereupon, the cam plate will fall backwardly with link 41, presenting its outer inclined edge for engagement with the descending pin 20 which will thereupon cause outward tilting of the utensil in lowering, owing to the sloping outer edge of the cam plate, as clearly shown. By merely manipulating the thumb terminal 46, the cam may be thus rendered operative or inoperative.

When the device is utilized with a fork terminal 47, as indicated in Figs. 6 and 7, it is desirable that the fork shall be thrust outwardly toward the user at the termination of its upward movement, for which purpose the upper portion of utensil holding arm 36 is provided with a right angle bracket extension 48, adapted to come into interfering engagement with the arm 49 of an adjustable abutment member 50 pivoted to the upright at 51. By adjusting such member, it may be rendered operative or inoperative as will be readily understood, so as to effect the desired movement.

When the fork 47 is utilized in the manner just described, we preferably provide a separate dish or utensil E mounted in the same manner as plate 7, or thereupon, and of considerable relative length so as to be capable of being shifted laterally, as desired, within range of the vertically movable fork throughout its length. By this means, portions of food may be impaled by the fork and lifted within range of the

mouth of the user as the holding vessel E is gradually shifted.

For the purpose of providing for drinking, a cup or other suitable vessel 52 is mounted in a receiving ring 53 provided with a pivoting pin 54 extending into a receiving thimble or ferrule 55. Pin 54 is provided with a limiting abutment 56 allowing the cup to be swung forwardly as desired by the user, and limiting it against backward tipping. Holding bracket 55 is adjustably mounted for vertical setting in the upper edge portion of plate 22 by means of a stud and securing set screw 57 engaging a slot 58. as will be readily understood.

At any convenient position along the front portion of base 2, it is provided with a clip device 59 for the purpose of holding a piece of toast, bread, or the like, and within easy reach of the user.

In order to reduce sliding friction of the vessel holding plate 7, it may be mounted on rows of rolling bearings, as balls 60 between guide bar 8 and an inner bar 61, as clearly shown in Fig. 10.

Various other attachments may be made in the way of conveniently providing for the holding of separate pieces or portions of food in the same manner without interfering with the main operative functions of the machine, and which are merely convenient attachments or additions not involving inventive subject matter.

The construction and operation of the apparatus will be readily understood and appreciated from the foregoing description. It is suitably proportioned as to height and its various dimensions to accommodate itself to the user when seated in front of it. By manipulating the lever arm 12 through the knee attachment, the dish or vessel-supporting plate may be moved to the right or to the left to enable all parts of it, or of the several individual vessels, to be placed within reach of the particular utensil being used. The main operative mechanism enables the user to move the utensil, *i. e.*, spoon or fork, at any desired speed, or to stop it at will, so that aside from the cutting of such food as may be eaten by a fork, all that is necessary for an attendant to do is to fill the dish or vessel with the prepared food and the drinking cup with liquid, as coffee, tea, etc.

The device is entirely practicable in operation and of great convenience and usefulness to those who are crippled in the manner indicated. It enables them to practically feed themselves, relieving the user of a sense of helplessness, and avoiding the necessity of an attendant to a great extent.

The invention may be changed or varied in different details of construction by the skilled mechanic, but all such changes are to

be understood as within the scope of the following claims.

65

What I claim is:

1. Self-feeding apparatus consisting of a food holding utensil and a pivoted supporting arm therefor having a guiding projection, means for raising and lowering the pivoted arm, a vertically arranged controlling cam for said projection, and pivotally mounted supports therefor.

2. Self-feeding apparatus consisting of a food holding utensil and a pivoted supporting arm therefor, having a guiding projection, means for raising and lowering the pivoted arm, a vertically arranged controlling cam for said projection, pivotally mounted supports therefor, and an adjusting device for changing the position of the cam supporting mechanism.

3. Self-feeding apparatus consisting of a food holding utensil and a pivoted supporting arm therefor having a guiding projection, means for raising and lowering the pivoted arm, a vertically arranged controlling cam for said projection, pivotally mounted supports therefor, and an adjusting device adapted to engage one of said pivotal supports.

4. The combination with a supporting plate and a vertically movable pivoted utensil carrier provided with a controlling projection; of a cam plate and means pivotally connecting it with the support.

5. The combination with a supporting plate and a vertically movable pivoted utensil carrier provided with a controlling projection; of a cam plate and means pivotally connecting it with the support, and an adjusting device for changing the position of the controlling cam on the support.

6. In combination with a supporting plate and a pivotally mounted utensil arm having a controlling projection; a pair of links pivoted to the supports, a controlling cam adapted to engage said projection, and an adjustable abutment for one of said pivotal supports.

7. In combination with a food holding utensil and means for actuating it, a laterally movable food receiver, a pivoted operating arm having a knee engaging fork, and means flexibly connecting said arm with the food receiver.

8. In combination with a food holding utensil and means for actuating it, a laterally movable food receiver, a pivoted operating arm having a knee engaging fork, means flexibly connecting said arm with the food receiver, and guiding devices for said flexible connecting means.

In testimony whereof I hereunto affix my signature.

FORREST R. MAGUIRE.
